UNITED STATES PATENT OFFICE.

RALPH B. HOSNER, OF SAN FRANCISCO, CALIFORNIA.

BEDSPRING.

Application filed May 4, 1921. Serial No. 466,667.

To all whom it may concern:

Be it known that I, RALPH B. HOSNER, a citizen of the United States, and a resident of the city and county of San Francisco, State of California, have invented a new and useful Bedspring, of which the following is a specification.

My invention relates to bed springs and an object of the invention is to provide means for preventing excessive lateral movement of the upper portion of the spring.

My invention possesses other objects and features of advantage, some of which, with the foregoing, will be set forth in the following description of my invention. It is to be understood that I do not limit myself to the showing made by the said description, as I may adopt variant forms of my invention within the scope of the claim.

Referring to the drawings: Fig. 1 is a plan view of my bed spring, portions being broken away to disclose the structure. Fig. 2 is a vertical sectional view taken in a plane indicated by the line 2—2 of Fig. 1.

The bed spring of my invention comprises a lower frame 2 formed preferably of structural steel members of suitable section and a border wire 3 forming an upper frame. Coil springs 4 are interposed between these frames, resting on cross bars 6 in the lower frame, at their upper ends connected together and to the border wire in the usual way.

Midway of each longitudinal side of the bed spring a bar 7 is pivotally attached to the border wire and extends downwardly and inwardly to a pivotally mounted block 8, thru which it passes forming a loose sliding fit therein. The end of the bar 7 is provided with a stop 9 for limiting the upward and outward movement thereof.

Pivoted to the bar 7 intermediate of its ends is a link 10 also pivoted to the longitudinal side bars of the lower frame 2. A coil spring 11 connects the link and bar adjacent their lower ends as shown in Fig. 2.

When the bed of which the spring forms a part is occupied, the coil springs are compressed and the bars are pushed downwardly and inwardly thru the blocks 8, such movement being resisted by the coil springs 11. Lateral movement of the upper frame within limits may take place, the limit on

either side being reached when the stop 9 on the bar on that side engages the pivoted block 8. When one sits on the edge of the bed there is a tendency toward lateral movement of the upper frame but such movement is checked first by the resilience of the spring 11 on that side, and secondly by the engagement of the stop 9 on the opposite side with the block 8. Sudden shock is of course avoided by the resilience of the border wire, the general effect of the mechanism shown being to resiliently hold the border wire and upper frame in proper relation to the lower frame.

From the above it will be observed that the bar 7 without the link 10 or spring 11 will function as indicated, the coil springs 4 at the edge of the structure tending to keep the frames apart and the bars 7 in the positions shown in Fig. 2. In this case when one sits on the edge of the bed the bar on the opposite side of the bed prevents too great a lateral displacement, its effect being cushioned by the resilience of the connecting border wire. I prefer however to use the structure shown since experience has taught me that a more stable structure is secured by supplementing the action of the springs 4 by the tension springs 11.

In the drawings I have shown but one bar on each side of the spring. It is of course obvious that more than one could be used if desired. Since however displacing stresses are applied to the structure almost invariably in the middle of the side, one stabilizing means such as I have shown is amply sufficient in the majority of cases.

I claim:

A bed spring comprising a bottom frame, an upper frame, coil springs interposed between said frames, a bar pivotally mounted on each longitudinal side of the upper frame and extending downwardly and inwardly to the bottom frame, means for slidably mounting said bars in the lower frame, means for limiting the upward movement of said bars in said mounting means, a link pivoted to each bar and to the lower frame, and a coil spring interposed between each bar and the connected link.

In testimony whereof, I have hereunto set my hand.

RALPH B. HOSNER.
